UNITED STATES PATENT OFFICE.

CHARLES N. NEWCOMB, OF OMAHA, NEBRASKA.

HAND-LOOM.

SPECIFICATION forming part of Letters Patent No. 373,246, dated November 15, 1887.

Application filed May 27, 1886. Serial No. 203,430. (No model.)

To all whom it may concern:

Be it known that I, CHARLES N. NEWCOMB, of Omaha, in the county of Douglas and State of Nebraska, have invented a new and useful 5 Improvement in Hand-Looms, of which the following is a full, clear, and exact description.

My improvements relate specially to hand- 10 looms for weaving rag carpets; and the invention consists in novel features of construction and arrangement of parts, as hereinafter described, and pointed out in the claims.

Reference is to be had to the accompanying drawings, forming part of this specification, in 15 which similar letters of reference indicate corresponding parts in all the figures.

Figure 1 is a vertical transverse section of a loom containing my improvements. Fig. 2 is a plan view of the same. Fig. 3 is a rear elevation with the warp-beam partially broken 20 away. Fig. 4 is a detail view, on an enlarged scale, of the means for operating the crank-shaft, the cam on the end of the said shaft being of a modified form. Fig. 5 is a similar view 25 viewed from the opposite side and with the parts in different positions. Fig. 6 is a detail perspective view of one of the pickers and a portion of one of the picker-sticks.

In its general construction the loom is as usual.

30 A is the warp-beam; B B, the heddles, fitted to slide in guides g; C, the vibrating lay, consisting of swords or side standards, a a, carrying bed b and connected at their lower ends by a cross-bar, d.

35 D is the front or breast roller, and E the cloth-roller.

Upon longitudinal rails e is mounted a shaft, f, provided at one end with a double crank, from which pitmen g² pass to and are connected 40 to the heddles B. On the shaft is a ratchet-wheel, h.

i i are arms having their outer ends bent over for the attachment of the springs a'. i' i' are shorter arms upon the opposite sides of the 45 ratchet-wheel h. Through the upper end of each pair of connecting-straps l l, the end of the shorter arms, i' i', and the middle of the arms i i is passed a bolt, i⁴, which bolt forms the pivot of the pawl k, all as clearly shown in 50 Figs. 4 and 5. The lower ends of the four straps l enter a mortise in a bar, m, and are connected

therewith by a bolt passing through the bar and straps. The bar m is fitted to slide vertically on depending pins n, secured between the fixed rails e.

55

o is an eccentric on shaft f between the arms of the forked upper end of a piece, p, that is held to rail e by a cross-arm, b', attached by cleats or guides c', so as to permit side movement of the piece p, and the lower end of the forked piece p strides a trigger, q, that is hung on the frame and passes through a loop, q', on the under side of the bar m.

r r are stirrups hung on the lower bar, d, of the lay, with their lower ends bent inward toward the trigger q, and connected at their upper ends to the picker-sticks s by straps t. Springs t' are interposed between the stirrups and straps and the stirrups are connected by a strap, t".

65

The picker-sticks are pivoted on the pins u, on which the lay swings. The picker-sticks extend below their pivots, and their lower ends can be connected by a cord, a'', having an interposed spiral spring, b'', so that the picker-sticks can be held at the outer ends of the boxes 70 when not in use.

75 On the back of the standards a of the lay triangles v are attached, and these are connected by short rods d' to the slide-bar m, so as to cause the bar to rise and fall as the lay moves forward and back, and thus give movement to straps l and pawls k, so as to cause intermittent rotation of ratchet-wheel h. The wheel h is moved a half-revolution by the action of the 80 two pawls at each complete reciprocation of the lay, and the heddles thus shifted.

85 The rotation of the shaft f with wheel h causes the shifting of piece p by eccentric o, and the trigger q is thereby shifted above the bent ends 90 of the two stirrups r alternately, so that, the trigger being pressed down by beam m, the picker-sticks s are operated in alternate order.

95 The back beam, e', over which the warps pass, is hung on pivots f', and is connected by loosely-jointed arms g' to the posts h', that project down between rails e, and are supported thereon by spiral springs i'. When bar m rises, as before described, it lifts the posts h' slightly, thereby moving the beam e' back far enough to strain 100 the warp just at the moment the reed strikes the rag filling, which insures its being beaten

up closely. As the lay returns, the beam e' comes forward again and the warps are slackened enough to permit of the shed opening widely and easily.

- 5 For giving tension to the warps, straps h' pass around the heads l' of beam A, and are connected to levers m' , that will carry adjustable weights m^2 . The front roller, D, over which the carpet passes, is provided with sharp pins 10 for holding the fabric. The winding-roller E is operated by a pawl, a' , hung on the end of a weighted lever, n' , which is raised by contact of a projection on the lay-standard a , so that the pawl is caused to act on a ratchet, o' , on the 15 roller when the lever again falls. The roller D is moved intermittently in the same manner by a weighted lever, p' , carrying two pawls, a^2 , so as to move the roller or take up the length of only a half-notch if that is all that the strain 20 will permit. The tension caused by lever p' is always the same, however large the roll on roller E may be, and the strain being entirely on roller D the weight on lever n' is just enough to roll up the carpet.
- 25 The picker-sticks project through slots in the shuttle-boxes r' and are provided with pickers s' , made of sole-leather and cupped on the side to receive the shuttle end, and the sticks pass through loops at the backs of the pickers, 30 whereby the horizontal movements of the pickers are permitted. The front of each box is formed by a pivoted piece, t' , having a beveled projection at its outer end that is acted on by

the picker s' when the shuttle enters the box, so as to press the front end or portion of the 35 piece t' inward against the shuttle, thereby locking the shuttle firmly in the box until the picker starts forward, when the piece t' is opened or spread by the spring u' on its outer end.

40 For operating the loom the lay is provided with a handle, v' . In the forward position of the lay the warps are straight, the ratchet-wheel h having made but a quarter-revolution, and they are strained by the beam e' . The weights 45 on levers n' p' then act to take up the slack caused by the blow of the lay. At the backward movement of the lay the warps slack, the shed opens, the shuttle is thrown, and levers n' p' are raised, so that the pawls a' a^2 move 50 down and engage again.

Having thus described my invention, what I claim as new, and desire to secure by Letters Patent, is—

1. The combination of crank-shaft f , pitmen g^2 , heddles B, ratchet h , pawls k , arms i , straps l , and slide-bar m , substantially as described, for operation as specified.

2. The combination of pivoted beam e' , arms g' , posts h' , springs i' , and slide-bar m , 60 substantially as and for the purpose specified.

CHARLES N. NEWCOMB.
